UNITED STATES PATENT OFFICE.

HARRY MACMILLAN, OF PHILADELPHIA, PENNSYLVANIA.

TANK LEVER.

Application filed May 11, 1926, Serial No. 108,236.

My invention relates to new and useful improvements in a tank lever, and has for its primary object to provide an exceedingly simple and effective method of attaching a lever to a fulcrum plate in order to considerably reduce the cost of manufacturing such articles.

Another object of the invention is to provide a unique method of connecting the fulcrum plate with the nipple, whereby the former is held in a certain fixed position relative to the latter.

A further object of the invention is to provide for an adjustment whereby the lever 15 may be connected with tanks having either thick or thin walls.

With these ends in view, this invention consists in the details of construction and combination of elements hereinafter set forth 20 and then specifically designated by the claims.

In order that those skilled in the art to which this invention appertains, may understand how to make and use the same, I will 25 describe its construction in detail, referring by numerals to the accompanying drawings forming a part of this application, in which:

Fig. 1 is a fragmentary top edge view of a flush tank showing my improved lever connected therewith.

Fig. 2 is a vertical, sectional view of the tank in the region of the lever mounting which is shown in elevation except for the fulcrum bracket and nut.

Fig. 3 is a side elevation of the fulcrum pin.

Fig. 4 is a view similar to Fig. 2, showing the lever on a tank having a wall thinner than the one shown in Fig. 2.

Fig. 5 is a rear face view of the tank wall showing only the fulcrum bracket mounted on the nipple.

Fig. 6 is a side elevation of the nipple.

Fig. 7 is a longitudinal sectional view 45 thereof.

Fig. 8 is an inner end view of the same.

In carrying out my invention as herein embodied, 10 represents the wall of a flush tank which oftentimes varies in thickness, and in order to clearly illustrate the manner in which my invention may be utilized, walls of two different thicknesses have been shown, the thinner one being illustrated in Fig. 4.

In a hole 11 in the tank wall is placed a 55 nipple 12 provided with a bore 13 of any

desirable cross sectional shape, and at one end of the nipple is a flange 14 which acts as an escutcheon to the hole 11, and adjacent said flange is preferably a rectangular portion 15, while beyond this, the inner end 60 of the nipple is threaded as at 16.

On the nipple is mounted a fulcrum bracket or plate 17, for which purpose said bracket is provided with a hole 18 having lugs 19 projecting thereinto, said lugs being 65 preferably two in number and diametrically opposite each other for registration with longitudinal grooves 20 in the inner end of the nipple so that when the bracket is on said nipple, the former will not rotate relative to 70 the latter.

The outer end of the fulcrum bracket 17 is preferably offset, as plainly indicated in Fig. 1, and has a hole therethru for the reception of the reduced end 21 of the fulcrum pin 22 which has a head 23 at the end opposite the reduced one, it being understood that the reduced end provides a shoulder 24, and this pin passes through the turned back end 25 and the parallel portion of the body of 80 the lever 26 with its reduced end projecting through the fulcrum bracket, in which position said reduced end is swaged, as indicated at 27, Fig. 1, so as to draw the shoulder 24 against a face of the fulcrum bracket. 85

The fulcrum bracket is placed upon the inner end of the nipple and drawn against the inner face of the tank wall where the latter is of such thickness that ends of the grooves 20 will be within or flush with the 90 inner face of said tank wall, where it is securely held by a nut 28 having threaded connection with the nipple; but where the wall of the tank is thinner than the space between the nipple flange and the adjacent ends of the grooves, washers 29 are inserted between the fulcrum bracket and the inner face of the tank wall, and as many of these washers may be used as are necessary to fill out the 95 space between the tank wall and the adjacent ends of the grooves.

Within the nipple is pivoted an operating lever 30 having its inner end underlying the lever 26 and provided with a suitable handle or knob 31 on the outer end. 105

Of course I do not wish to be limited to the exact details of construction as herein shown as these may be varied within the limits of the appended claims without departing from the spirit of my invention. 110

Having thus fully described my invention, what I claim as new and useful is:

1. A tank lever including a fulcrum bracket; a lever; a pin having a head on one end while the other end is reduced in diameter, said pin passing through the lever and fulcrum bracket with an enlargement swaged from the reduced end.
10. The herein described combination of a fulcrum bracket having a hole therethrough; a lever having a hole therethrough and a pin having a reduced end to provide a shoulder and having a head at the other end, said pin passing through the holes in the lever and fulcrum bracket with the shoulder in engagement with a face of said fulcrum bracket; and a swaged enlargement formed from the projecting reduced end.
20. In a device of the character stated a nipple longitudinally grooved; a fulcrum plate provided with a hole having lugs projecting thereinto for registration with the grooves in the nipple when the fulcrum plate is mounted on said nipple; and means having threaded connection with the nipple to hold the fulcrum bracket in place.
4. In a device of the character stated, a nipple to be mounted in a hole in the flush tank; a fulcrum bracket for mounting upon the inner end of said nipple; means to prevent rotation of the bracket relative to the nipple; and means occupying the space between the inner face of the tank wall and the fulcrum bracket.
30. In a device for the flushing of closets, a ball lever; a bracket; means of securing bracket; and a headed fulcrum pin passing through said lever and secured in said bracket.
35. In a device for the flushing of closets, a flush tank; a hole in a wall thereof; a sleeve secured in said hole; an end of said sleeve projecting into said tank, sides of said sleeve provided with grooves; a bracket; a hole in said bracket permitting it to encircle the inner projecting end of said sleeve; and lugs on bracket to engage grooves on said sleeve.
40. In testimony whereof, I have hereunto affixed my signature.

HARRY MACMILLAN.
